GASEOUS ELECTRIC DISCHARGE LAMP
DEVICEHenricus Gooskens, Eindhoven, Netherlands, as-
signor to General Electric Company, a corpora-
tion of New YorkApplication November 7, 1934, Serial No. 751,953
In the Netherlands November 9, 1933

6 Claims. (Cl. 176—122)

The present invention relates to a gaseous electric discharge lamp device generally and more particularly the invention relates to such devices the gaseous atmosphere of which consists of or 5 comprises the vapor of a relatively difficultly vaporizable metal, that is a metal the vapor pressure of which is less than 1 mm. at a temperature of 200° C.

In order to have an effective metal vapor pressure in the device during the operation thereof, that is, a vapor pressure such that the light emitted by the device is rich in rays characteristic of the metal vapor, the container of the device must be at an elevated temperature and a heat 10 conservator, such as an evacuated jacket, which reduces the dissipation of heat from the lamp container, is useful in this connection. The vapor pressure in vapor lamp devices is determined, in general, by the lowest temperature existing in 15 the container and during the operation of the device the surplus vaporizable metal is deposited on the part of the container having the lowest temperature.

The object of the present invention is to provide 20 means in a gaseous electric discharge vapor lamp device whereby the efficiency and the useful operating life of the lamp device is increased. Another object of the invention is to provide a lamp unit comprising an efficient, long-lived gaseous 25 electric discharge lamp device and a heat conservator for said lamp device. Still further objects and advantages attaching to the device and to its use and operation will be apparent to those skilled in the art from the following particular description.

In accordance with these objects the invention 30 comprises a heat source mounted in operative relation to the part of the lamp container which is at the lowest temperature during the operation 35 of the device which heat source revaporizes such quantity of the metal deposited on said low temperature container part that the vapor pressure in the lamp device is increased above that pressure which would exist in said lamp at the temperature 40 of said low temperature container part. Part of the vaporous material condenses again on said low temperature container part. The metal vapor is thus circulated and I have discovered that this circulation of the metal vapor increases the 45 efficiency of the lamp device considerably and slows up the depreciation of the lamp device, that is, the intensity of the light emitted by the 50 device diminishes very slowly during the life of the lamp device which, of course, increases the 55 useful operating life of the device.

When a continuous circulation of the metal vapor is desired the heat source is mounted and regulated in such manner that while the lowest temperature part of the container is heated thereby the temperature thereof still remains below 8 the temperature of the other parts of the container. When desired the vaporizable metal is heated intermittently and locally. An anode of the lamp device is used as the heat source, when desired, said anode having such structure that the 10 temperature thereof increases when the operating voltage of the lamp device increases.

A heat conducting element extending from the anode to the vaporizable material is useful in 15 transferring heat from said anode to said vaporizable material. I prefer an anode of wire, such as a wire ring of high melting point material, such as tungsten. The operating voltage of the lamp device increases when the vapor pressure falls below a certain value. The anode temperature thus 20 depends upon the vapor pressure and when the vapor pressure falls to the level at which the voltage between the electrodes increases the anode 25 temperature is increased by the more intense electron bombardment thereof and the vaporizable metal is heated to the vaporization temperature thereof. The vapor pressure is thus built up to the desired level and the desired operation of the lamp is resumed.

In the drawing accompanying and forming part 30 of this specification two embodiments of the invention are shown in which

Fig. 1 is a front elevational, partly sectional view of one embodiment of the invention, and

Fig. 2 is a perspective view of one element of the 35 embodiment illustrated in Fig. 1.

Fig. 3 is a front, elevational view of another embodiment of the invention.

Like numbers denote like parts in all the figures.

Referring to Fig. 1 of the drawing the new and novel lamp unit comprises a gaseous electric discharge lamp device and a heat conservator therefor. Said lamp device comprises a bulb-shaped container 1 having electrodes 3, 4 and 5 45 sealed therein, a starting rare gas therein, such as argon or neon, and a vaporizable material therein, such as sodium. The interior of said container 1 is divided into two chambers, a stem chamber and an electrode chamber, by the sep- 50 tum 2, such as a resilient chrome-steel or glass disc. The electrode 3 is the cathode and consists of a filament, such as a tungsten or nickel filament, wrapped around said first named filament, and a coating of electron emitting material, such 55

as barium oxide, applied to said filaments. Said cathode 3 is wound in the form of a helix. Said electrode 4 is an anode and consists of a metal strip bent in the form of a ring. Said electrode 5 is another anode and is made of a thin wire, such as a tungsten wire, having a diameter of about 0.75 mm. Said anodes 4 and 5 are equidistant from said cathode 3 and are mounted on opposite sides of said cathode 3. The end of 10 said container 1 has a protruding cup-shaped part 7 and an extension 6 of the anode 5 extends into said cup-shaped part 7. The anode 5 and the extension 6 thereof is made of a single piece of bent wire looped as shown in perspective in 15 Fig. 2.

The leads 8 of the electrodes 3, 4 and 5 are of nickel, for example, and are surrounded over their entire length by tubes 9 of insulating material, such as magnesium oxide tubes. I prefer to 20 allow a small space between said leads 8 and said tubes 9 so that the spaces on either side of the 25 septum 2 are connected by long, narrow passages. These passages facilitate the manufacture of the gaseous electric discharge lamp device by making it possible to evacuate all parts of said 30 container 1 through a single exhaust tube communicating with either of the spaces in said container 1. After the lamp device has been operating a few hours the passages are closed by deposits 35 of condensed metal vapor and the spaces on either side of the septum 2 are completely closed off from each other during the rest of the life of the gaseous electric discharge lamp device.

The welded joint between the anode 5 and the 35 lead 8 therefor is surrounded by the insulating tube 9 so that said joint is protected from the gaseous electric discharge during the operation of the lamp device.

The container 1 has a starting, rare gas therein, such as argon or neon, at a pressure of approximately 1 to 10 mm. and a quantity of one or more relatively difficultly vaporizable metals, that is a metal having a vapor pressure of less than 1 mm. at a temperature of 200° C., is introduced into the part of said container 1 surrounding 40 said electrodes 3, 4 and 5. Sodium, cadmium, thallium, magnesium, potassium, lithium and zinc are examples of metals having such pressure at this temperature. When the vapor of such metals 45 is at an effective pressure in said lamp device the light emitted by the device is rich in rays characteristic of the metal vapor. In the embodiment of the invention illustrated in the drawing the vaporizable material is sodium.

50 When desired the anode leads are electrically connected so that arc discharges take place simultaneously between said cathode 3 and each of the anodes 4 and 5. When the lamp device is operated as a rectifier on alternating current 55 the anodes 4 and 5 are connected separately to the alternating current source.

Said container 1 is surrounded by a double-walled glass jacket 10 having the space between the walls thereof evacuated and which reduces 60 the dissipation of heat from the walls of said container 1. The container 1 and the jacket 10 are both equipped with bases, of insulating material when desired, which frictionally engage with the 65 socket 11. A resilient heat insulating ring 12 consisting of a coiled spring covered with asbestos, for example, is interposed between said container 1 and the inner wall of said jacket 10 and is located at a part of said container 1 adjacent 70 said septum 2. Said ring 12 closes off the space surrounding the part of container 1 enclosing said

electrodes 3, 4 and 5 from the ambient atmosphere of the lamp unit.

The structure of the lamp unit is such that the protruding part 7 is at a lower temperature than the other parts of the lamp device which form 5 the enclosing walls of the space about the electrodes 3, 4 and 5. While this result may be obtained in many ways, as disclosed in co-pending application Serial Number 750,713, filed October 30, 1934, the inventors being Gilles Holst and 10 Willem Uyterhoeven, in the embodiment illustrated in Fig. 1 of the drawing this result is obtained by mounting the anode 4 closer to the septum 2 than the distance between the anode 5 and the end of container 1. The upper portion 15 of this part of container 1 is thus heated to a higher temperature by the discharge between said electrodes 3, 4 and 5 than the lower portion of this part of container 1. The protruding part 7, which is at the greatest distance from the discharge, is at the lowest temperature during the 20 operation of the lamp device and deposits of condensed vapor take place in said part 7.

The wire anode 5 is of such diameter that when 25 the vapor pressure in the lamp device and the arc discharge voltage are at values such that the lamp device operates at its maximum efficiency the 30 temperature of said wire anode 5 is relatively low and the wire 6 conducts very little heat to the solid sodium deposited in the cup-shaped part 7 35 of the container 1. When the vapor pressure diminishes to the extent that the arc discharge voltage increases the temperature of the anode 5 increases as pointed out heretofore. The heat conducted by said wire 6 from said anode 5 to the 40 sodium in said cup 7 is thus increased and the sodium is heated to the vaporization temperature 45 thereof and vaporizes. The vapor pressure is thus restored to normal and normal operating conditions again exist in the lamp device. The 50 above described structure and operation of the lamp device is not only advantageous during the operation of the lamp device but also is advantageous in the starting of the lamp device since during the starting period the vapor pressure is rapidly raised to the effective pressure thereof and the lamp device emits an intense light shortly after it is started into operation.

The embodiment of the invention illustrated in Fig. 3 of the drawing is similar in all respects 55 to that shown in Fig. 1 except that in this embodiment the anode 5 is similar in structure to the anode 4 and both said anodes 4 and 5 are connected to and supported by the said current lead. A small heating element 13, which is an 60 electric resistance, is connected to the anode 5 and to one of the leads of cathode 3. The end of container 1 is substantially conical in shape and the heater 13 is mounted closely adjacent the conical end. A coating 14 of a heat conducting material such as graphite, which increases the radiation of heat from the coated portion of 65 said conical part is applied to said conical part. The coated portion of the conical part is at the lowest temperature of any part of the electrode 70 chamber of said container during the operation of the lamp device. When the sodium vapor condenses at the coated container part the condensed sodium is still sufficiently liquid to flow down to the part of said container heated by the element 13 by which it is revaporized. Continuous circulation of the sodium vapor thus takes place which increases the efficiency and the useful life of the lamp device.

While I have shown and described and have 75

pointed out in the annexed claims certain novel features of the invention, it will be understood that various omissions, substitutions and changes in the forms and details of the device illustrated and in its use and operation may be made by those skilled in the art without departing from the broad spirit and scope of the invention.

What I claim as new and desire to secure by Letters Patent of the United States is:—

10 1. A gaseous electric discharge lamp device comprising a container, electrodes sealed therein, a starting gas and a quantity of vaporizable material therein, means for maintaining a part of said container at a lower temperature than the other parts thereof and a heater mounted in said container adjacent the lowest temperature part thereof.

15 2. A gaseous electric discharge lamp device comprising a container, electrodes sealed therein, a starting gas and a quantity of vaporizable material therein, means for maintaining a part of said container at a lower temperature than the other parts thereof and a heater mounted in said container adjacent the lowest temperature part thereof, the temperature of said heater being controlled by the discharge current between said electrodes.

20 3. A gaseous electric discharge lamp device comprising a container, electrodes sealed therein, a starting gas and a quantity of vaporizable material therein, means for maintaining a part of said container at a lower temperature than the other parts thereof, one of said electrodes being an anode the temperature of which is responsive to changes in voltage in the discharge between

said electrodes, and means to conduct the heat from said anode to the vicinity of the lower temperature part of said container.

25 4. A gaseous electric discharge lamp device comprising a container, electrodes sealed therein, a starting gas and a quantity of vaporizable material therein, means for maintaining a part of said container at a lower temperature than the other parts thereof, one of said electrodes being a wire ring anode the temperature of which is responsive to changes in voltage in the discharge between said electrodes, and means to conduct the heat from said anode to the vicinity of the lower temperature part of said container.

30 5. A gaseous electric discharge lamp device comprising a container, electrodes sealed therein, a starting gas and a quantity of vaporizable material therein, means for maintaining a part of said container at a lower temperature than the other parts thereof, said electrodes comprising two anodes and a cathode and a heater mounted in said container adjacent the lowest temperature part thereof, said heater being a resistance connected in series with one of said anodes and said cathode.

35 6. A lamp unit comprising in combination a heat conservator and a gaseous electric discharge lamp device comprising a container, electrodes sealed therein, a starting gas and a quantity of vaporizable material therein, means for maintaining a part of said container at a lower temperature than the other parts thereof and a heater mounted in said container adjacent the lowest temperature part thereof.

HENRICUS GOOSKENS. 35
